UNITED STATES PATENT OFFICE.

JOHN J. COLLINET AND HENRY T. COLLINET, OF CHICAGO, ILLINOIS.

CALIPERS.

No. 887,068.

Specification of Letters Patent.

Patented May 12, 1908.

Application filed July 19, 1907. Serial No. 384,623.

To all whom it may concern:

Be it known that we, JOHN J. COLLINET and HENRY T. COLLINET, citizens of the United States, residing at Chicago, in the county of Cook and State of Illinois, have invented certain new and useful Improvements in Calipers, of which the following is a specification.

Our invention relates to calipers and particularly contemplates the provision of an improved means whereby the legs thereof and their respective engaging points may be spring pressed against the object being gaged to obtain an absolutely correct measurement.

Our invention further and specifically resides in the following features of construction, arrangement and operation, which will be hereinafter described with reference to the accompanying drawings forming a part of this specification, in which like numerals are used to designate like parts throughout the several figures, and in which

Figure 1 is an elevation of a pair of outside calipers in their practical application and constructed in accordance with our invention. Fig. 2 is a similar view of a pair of inside calipers constructed in accordance with our invention, and Fig. 3 is an enlarged detail, partly in section, of parts to be herein-after specifically referred to.

In the accompanying drawings, A and B represent the respective legs of a pair of calipers, pivoted at C to swing with relation to one another and gage an object such as D.

The leg B is provided with an engaging point E at its free end, while according to our invention we provide a leg A substantially shorter in length than the leg B, and pivot a supplemental leg 1 at the free end thereof of such length and shape beyond its pivot 2 as to form with the leg A, a member corresponding exactly in shape and size to the leg B. The supplemental member 1 is curved to lie upon the leg A for a considerable portion of its length, being provided with a transverse slot 3 and a longitudinal slot 4 leading from said transverse slot 3. The supplemental leg 1 is further constructed at its rear end to form an indicator 5 resting above graduations 6 arranged transversely upon the leg A. The leg A is further provided with a rigid threaded stud 7 extending upwardly therefrom through the transverse slot 3 of the supplemental leg 1, and provided with a flat spring 8 secured therein and

extending rearwardly therefrom within the narrow longitudinal slot 4 of said leg 1. An adjusting screw 9 is adapted to engage upon the stud 7 and to bear upon the supplemental leg 1 to press the same tightly against the leg A and lock the same in a desired degree of adjustment.

The operation of our invention is as follows: The user having first loosened the adjusting screw 9, the indicating points E and 10 may be engaged about the object D to more readily and actively gage the same. In this operation the supplemental leg 1 will be free upon its pivot while spring pressed by the flat spring 9 to force its engaging point 10 inwardly toward the engaging point E of the leg B in the case of the outside calipers shown in Fig. 1 and outwardly away from the engaging point E of the leg B in the case of the inside calipers shown in Fig. 2. As this fine adjustment is had, the operator must note particularly the indications of the pointer 5 upon the graduations 6, and while the calipers are engaged about the object, or when removed, the adjusting screw 9 may be rotated to securely lock the supplemental leg 1 at the exact adjustment, thus obtaining a better and more accurate gage of the object.

It will be seen that the same construction may be employed in the inside caliper as shown in Fig. 2, in gaging the bore F.

Having thus fully described our invention, we claim:

1. The combination in a caliper comprising a long leg provided with an engaging point at its outer end, of a short leg pivoted to said long leg, a supplemental member pivotally connected with one end adjacent the outer end of said short member and forming a continuation of and completing said short leg said supplemental member being formed at its rear end to provide an indicator and having a transverse slot therein, said short leg, being transversely graduated adjacent said indicator and having a threaded rigid stud projecting upwardly therefrom within said transverse slot, spring means for forcing the outer engaging end of said supplemental member against the face of the object to be gaged, and an adjusting screw adapted for engagement upon said threaded stud to lock said supplemental member when in the desired degree of adjustment, substantially as described.

2. The combination in a caliper comprising a long leg having an engaging point at its

end, and a short leg pivoted to said long leg, of a supplemental member pivotally mounted with one end adjacent the end of said short leg and forming a continuation thereof 5 and completing the same, said supplemental member being formed at its rear end to provide an indicator, and having a transverse slot therein and a narrow longitudinal slot extending from said transverse slot, said 10 short leg being transversely graduated adjacent said indicator and being provided with a threaded rigid stud extending upwardly therefrom within said transverse slot, and having a flat spring secured within said stud 15 and extending therefrom within said longi-

tudinal slot to said supplemental member to normally force the outer engaging end thereof against the face of the object to be gaged, and an adjusting screw adapted for engagement upon said rigid stud to securely lock 20 said supplemental member when in the desired degree of adjustment, substantially as described.

In testimony whereof we affix our signatures in presence of two witnesses.

JOHN J. COLLINET.
HENRY T. COLLINET.
